ATTORNEYS

UNITED STATES PATENT OFFICE.

CHARLES P. SCHACHMAN, OF CONGRESS, ARIZONA TERRITORY.

ENVELOP-FASTENER.

SPECIFICATION forming part of Letters Patent No. 635,000, dated October 17, 1899.
Application filed April 3, 1898. Serial No. 711,530. (No model.)

To all whom it may concern:

Be it known that I, CHARLES P. SCHACHMAN, a citizen of the United States, and a resident of Congress, county of Yavapai, and Territory of Arizona, have invented certain new and useful Improvements in Envelop-Fasteners, of which the following is a specification, reference being had to the accompanying drawings, forming a part thereof, in which similar letters and figures of reference indicate corresponding parts.

This invention relates to improvements in envelop-fasteners, the object thereof being to provide a means for fastening envelopes or other similar packages in such a secure manner as to prevent opening thereof without destroying the envelop, whereby surreptitious opening and reclosing of envelopes while in transit is prevented.

20 The invention will be hereinafter fully described, and specifically set forth in the annexed claims.

In the accompanying drawings, forming part of this specification, Figure 1 is a perspective view of my improved fastener, showing the same in open position. Fig. 2 is a perspective view illustrating the device attached to an envelop closed and sealed, and Fig. 3 is a side elevation illustrating a slight structural modification.

30 In the practice of my invention I employ an upper plate A and a lower plate B. These plates are composed of resilient sheet metal, and they are preferably made integral with each other and bent upon a transverse line through the center of the plate. Upon the upper surface of the lower plate B, I place a sheet of fabric C and fasten the same to the said plate by means of points or spurs b, which are stamped from the said plate and form an integral part thereof. The upper plate A is provided at the center thereof with a series of angularly-extended pointed tongues a, which are stamped from the surface of the said plate and bent at an angle outwardly. The outer edge of the said plate A is also provided with any suitable number of pointed tongues a'. These tongues form an integral part of the plate and they are bent at 50 an angle inwardly.

In the operation and use of the invention the plate A is placed upon the inside of the

sealed envelop, and it extends through a slot or slit 1, formed through the back of the envelop. Having placed the plate in position, 55 the upper plate B is bent over upon the outer surface of the envelop and given a sharp blow with a flat instrument, which causes the angular points formed thereon to pass through the material composing the envelop and also 60 through the fabric C, interposed between the two said plates, and by contact with the lower plate these said points are bent and clenched, thus retaining the envelop in a securely-fastened condition, and the fabric sheet prevents 65 accidental tearing of the paper envelop while the same is in transit.

In the modification illustrated by Fig. 3 of the drawings I use an upper plate D, of any suitable contour, and a lower plate E of corresponding shape. The upper plate is supplied with pointed tongues d and d', and the lower plate is provided with a fabric sheet F, which is secured by means of the bent spurs e.

Having thus described my invention, what I claim as new, and desire to secure by Letters Patent, is—

1. An envelop-fastener comprising an upper plate having a series of centrally-located 80 pointed tongues extended from the under surface thereof at an angle outwardly, and a series of pointed tongues extended from the edge thereof at an angle inwardly, in combination with a lower plate having no projecting tongues or spurs and having its face opposite the tongued face of the upper plate covered with a fabric secured thereto and into which fabric the tongues of the upper plate bind when clenched, substantially as 85 shown and described.

2. In an envelop-fastener, the combination of an upper and a lower plate formed of a single piece of sheet metal and bent into shape relative to each other, a sheet of fabric secured to and covering the upper surface of the lower plate, and a series of tongues formed integral with the upper plate and extending centrally therefrom at an angle outwardly, and adapted for being bent upon the upper 95 surface of the lower plate by contact therewith, and a series of pointed tongues extended from the edge of the said upper plate at an angle inwardly, said tongues of the upper

plate entering and binding under the fabric face of the lower plate when the same are clenched, substantially as shown and described.

5. 3. The combination with an envelop, of a fastener comprising an upper and a lower metallic plate, the upper plate having a series of pointed tongues extended therefrom and the lower plate having a sheet of fabric secured to and covering its face which is opposite the tongued face of the upper plate, the tongues of the upper plate adapted to pass through the fabric and the material comprising

ing the envelop for the purpose of fastening the same and bind under the fabric face of the lower plate when they are clenched, substantially as shown and described.

In testimony that I claim the foregoing as my invention I have signed my name, in presence of two witnesses, this 24th day of March, 1899.

CHARLES P. SCHACHMAN.
